(57) **CLAIM**

The ornamental design for a bracket for fixing a sprinkler, as shown and described.

DESCRIPTION

FIG. 1 is a perspective view of the ornamental design of the present invention;

FIG. 2 is a front view of the ornamental design of the present invention;

FIG. 3 is a rear view of the ornamental design of the present invention;

FIG. 4 is a left side view of the ornamental design of the present invention;

FIG. 5 is a right side view of the ornamental design of the present invention;

FIG. 6 is a top view of the ornamental design of the present invention;

FIG. 7 is a bottom view of the ornamental design of the present invention;

FIG. 8 is a first reference view of the ornamental design of the present invention; and,

FIG. 9 is a second reference view of the ornamental design of the present invention.
